UNITED STATES PATENT OFFICE.

ALLAN C. SARGENT, OF WESTFORD, MASSACHUSETTS.

JACK.

1,000,186.

Specification of Letters Patent. Patented Nov. 21, 1911.

Application filed April 12, 1911. Serial No. 620,563.

To all whom it may concern:

Be it known that I, ALLAN C. SARGENT, a citizen of the United States, residing at Westford, in the county of Middlesex and State of Massachusetts, have invented a new and useful Jack, of which the following is a specification.

This invention relates to a jack capable of general use but particularly suitable for 10 jacking up automobiles to permit the adjustment of the wheel brakes and for other purposes. In adjusting the wheel brakes, to get an even adjustment it is essential to have both the wheels jacked up so that the 15 tension of each brake and its application can be easily gaged.

This invention is designed to take the place of a pair of independently operated jacks which are ordinarily used for raising 20 the opposite ends of the axle tube.

The principal objects of the invention are to provide for accomplishing these results; to provide a very strong lift so that the jack can be used for the heaviest kind of trucks; 25 to provide for the adjustment of the supporting means for the ends of the shaft toward and from the center so as to permit of the selection of the most desirable point on the axle to apply the lift; to provide a 30 construction in which the supporting devices project materially above the frame work so that the latter can be low enough to clear the case of the differential and other downwardly projecting parts; to provide a 35 construction which can be operated either by an ordinary bit-brace or a socket appliance; and in general to provide a simple, convenient, and inexpensive apparatus for this purpose.

40 Further objects and advantages of the invention will appear hereinafter.

Reference is to be had to the accompanying drawings, in which—

Figure 1 is a side elevation of a jack constructed in accordance with this invention; 45 Fig. 2 is a plan of a portion thereof with the parts appearing in section; and Fig. 3 is a sectional view on the line 3—3 of Fig. 1.

The device is shown in a form in which 50 it is entirely supported by a frame 10 consisting of a pair of end pieces and a plurality of longitudinal bars 11 which are parallel with each other and constitute guides. Near the center of the frame is a skeleton 55 box 12 having a transverse shaft 13 bearing on one end thereof, and provided on its

end with a non-circular projection 14 adapted to be rotated by any socket device or an ordinary bit-brace. On the inner end of the shaft it is shown as provided with a bevel gear 15 which meshes with a gear 16 on a longitudinal shaft 17. This gear and the shaft have a bearing 18 on one side of the frame 12 and the gear is held in position by a collar 19 fixed on the shaft so that the rotation of the shaft 13 will rotate the shaft 17.

The shaft 17 is provided with worms 20 on opposite ends shown as arranged right handed. Mounted to slide back and forth on the guides 11 are a pair of frames or carriers 21. Each is provided with a central slot 22 through which the worm shaft passes and in which is located a wheel 23 having worm teeth thereon meshing with the worm 25 shaft. This wheel is provided with a central passage 24 which is screw threaded. Through this passage passes a screw 25. This screw has bearings in an upwardly extending projection 26 on the carrier 21 and at the top carries a support 27. No special means is provided for preventing the rotation of the screw 25, as in use it cannot rotate when the automobile axle is supported by the two supports 27. When not in use either one of the screws can be rotated to adjust it vertically.

In operation the shaft or axle near its opposite ends is placed over the two supports 27 and the shaft 13 is rotated, in a direction 90 to raise these supports until they lift the axle sufficiently to get the wheels off the ground.

It will be observed that on account of the shape of the supports 27 they cannot rotate 95 after they support the axle. It will be seen also that on account of the fact that the only parts which project above the frame proper are the projections 26 and supports 27, the frame itself is low enough to clear the differential and other depending parts. The end 14 of the shaft 13 projects out where it can be reached readily from the rear of the vehicle when the device is applied to the rear axle and from the front 100 when it is applied to the front axle. At the same time the device is very simple, consists of few parts, and is strong and rigid, and it provides a sufficiently strong lift to make it 105 useful for the largest machines, although built small enough to be applied to the 110 smaller makes.

While I have illustrated and described a preferred embodiment of the invention, I am aware that many modifications can be made therein by any person skilled in the art without departing from the scope of the invention as expressed in the claims. Therefore I do not wish to be limited to all the details of construction herein shown and described, but

10 What I do claim is:-

1. In a jack, the combination of a frame comprising a set of rigid horizontal parallel guides, a pair of carriers independently movable along said guides, a pair of supports projecting upwardly from said carriers and comprising a screw housed in each carrier, a nut on each screw, and means located between the carriers and projecting transversely therefrom for rotating said nuts simultaneously for raising or lowering the supports.

2. In a device of the character described, the combination with a frame comprising horizontal rigid guides, of a pair of carriers mounted on said guides and adapted to move freely therealong toward and from each other, a pair of vertically movable supports on the carriers, a shaft on the frame parallel with the guides and having screw-

threads at its opposite ends, a pair of 30 toothed wheels meshing with the screw-threads for raising and lowering the supports, and a shaft at right angles to the first named shaft and projecting from the center of one side of the machine and connected 35 with the first named shaft for rotating it.

3. In a device of the character described, the combination of longitudinal guides, a pair of carriers independently adjustable along said guides, each having an upwardly extending projection, a pair of vertical screws mounted in said projections and extending above the same and having supports on their upper ends, each of said carriers having a slot therein, a nut for each of said screws mounted in each of said slots, said nuts having worm teeth on the outside thereof, a worm shaft parallel with the guides meshing at its opposite ends with the two worm nuts, and means between the carriers for rotating said shaft.

In testimony whereof I have hereunto set my hand, in the presence of two subscribing witnesses.

ALLAN C. SARGENT.
